UNITED STATES PATENT OFFICE.

OLIVER CROSBY, OF ST. PAUL, MINNESOTA, ASSIGNOR TO AMERICAN HOIST & DERRICK CO., OF ST. PAUL, MINNESOTA, A PARTNERSHIP.

ROPE-CLIP.

1,271,282.

Specification of Letters Patent.

Patented July 2, 1918.

Application filed January 22, 1918. Serial No. 213,145.

To all whom it may concern:

Be it known that I, OLIVER CROSBY, a citizen of the United States, residing at St. Paul, county of Ramsey, State of Minnesota, have invented certain new and useful Improvements in Rope-Clips, of which the following is a specification.

The object of this invention is to provide a rope clip of such construction that any tendency toward slippage of the ropes or rods therein will cause the clip to grip them more securely, and the harder the pull on the cables or rods the more firmly they will be clamped by the clip.

The invention consists generally in various constructions and combinations, all as hereinafter described and particularly pointed out in the claims.

In the accompanying drawings forming part of this specification,

Figure 1 is a side view, partially in section, of a rope clip embodying my invention,

Fig. 2 is an end view of the same,

Fig. 3 is a vertical sectional view through the clip.

Fig. 4 is a sectional view of a modified construction.

In the drawing, 2 and 3 represent the lapping ends of the rope, secured together by the clip. 4 is a U-shaped bolt arranged to straddle the rope and 5 is a block having sockets therein to receive the ends of the bolt which extends below the block and are provided with clamping nuts 6 which, when tightened on the threaded ends of the bolt, clamp it firmly on the rope. 7 is a secondary block or shoe, having a concave gripping surface 8 which has a comparatively long bearing on the rope or cable and opposing the gripping surface of the block 5. This block 7 has a comparatively large opening 9 therein, in which the U-shaped bolt is mounted, and the lower walls of this opening are curved, as at 10, to form cam surfaces on each side of the vertical axis of the bolt. The curved portion of the U-bolt normally rests in the center of this opening and between the cam surfaces, but when the block

is moved lengthwise upon slipping of the rope or rod, the bolt will slide and begin to climb one of the cam surfaces 10 and automatically increase the clamping or crushing strain of the clip on the rope.

The block 5 has upwardly extending portions 11 on opposite sides of the arms of the U-bolt and adjacent thereto, and when the rope begins to slip in the clamp these portions of the block, engaging the arms of the U-bolt, will brace and support it and resist the tendency to bend the bolt.

The clip may be made in various sizes and the block 7 may be varied in length to increase or decrease its gripping surface and the length of the cam surfaces for engaging the U-bolt.

In Fig. 4 I have shown a modified construction which consists in providing a block 12 having a gripping surface 8 for the rope and a wedge face 13 upon opposite sides of the U-bolt inclined inwardly and downwardly toward the center of the block and forming slightly inclined surfaces on which the U-bolt may slide to exert a further clamping action on the rope. Lugs 14 are preferably provided at the ends of the block 12 extending above said inclined or wedge surfaces.

I claim as my invention:

1. A rope clip comprising a U-shaped bolt, a block slidably mounted on the arms thereof, nuts mounted on the threaded ends of said arms, a secondary block loosely mounted on the curved portion of said U-bolt and having a cam bearing surface for said curved portion, and on which cam bearing surface the curved portion of said bolt is free to slide when it is moved by the slipping of the rope.

2. A rope clip comprising a U-shaped bolt, a block slidably mounted on the arms thereof and clamping nuts mounted on said arms for engaging said block, a secondary block between which and said first named block the lapping ends of the rope are clamped, said secondary block having a comparatively long opening therein with a seat for the curved portion of said bolt in the bottom of said

opening, a comparatively wide gap being formed on each side of said bolt between it and the end walls of said opening for freedom of movement of said bolt in said opening, the bottom of said opening being curved slightly from said seat to meet said end walls and forming cam surfaces over

which said bolt is moved by the pulling strain on the rope to increase the pressure of said secondary block thereon.

10

In witness whereof, I have hereunto set my hand this 12th day of January, 1918.

OLIVER CROSBY.
